United States Patent Office.

B. B. PERKINS, OF CHESTERTOWN, MARYLAND.

Letters Patent No. 74,936, dated February 25, 1868.

COMBINED BOILER AND HOT-AIR REGISTER.

The Schedule referred to in these Letters Patent and making part of the same.

TO ALL WHOM IT MAY CONCERN:

Be it known that I, B. B. PERKINS, of Chestertown, in the county of Kent, and State of Maryland, have invented a new and improved Combined Boiler and Hot-Air Register; and I do hereby declare the following to be a full, clear, and exact description of the same, reference being had to the accompanying drawings, forming part of this specification, and in which—

Figure 1 is a top view of my invention.

Figure 2 is a vertical section of the same, through the line $x x$ in fig. 1.

Similar letters of reference indicate corresponding parts in the two figures.

In this invention, a boiler connected with the register is attached to the side or end of the hot-air flues in houses, for the purpose of utilizing the heat conducted away by the walls of the flues, and of supplying hot water to the upper rooms of the house.

In order that others skilled in the art to which my invention appertains may be enabled to make and use the same, I will proceed to describe it in detail.

In the drawings, A A represent a hot-air flue, extending from the heating-furnace to the upper part of a house, and discharging its heated air into the room, through the register B. At C, I locate a boiler, having a spigot at D, and a lid at E, through which the boiler may be filled or emptied. I provide several apertures, $e e e$, in the top of my boiler, and attach to it a movable cover, F, swinging horizontally on a pivot, f, and having holes, $i i i$, which, as the cover is moved in one direction or another, will be brought into or thrown out of connection with the holes $e e e$ in the top of the boiler. When open, the steam will escape through them and moisten the hot air supplied to the room through the register, for the purpose of making it more wholesome.

The cover may be connected by a cord or wire H to the register, so that in proportion as the register is opened the apertures $e e e$ will also be opened, and the escape of steam into the flue be exactly proportioned to the quantity of hot air used in the room.

Having thus described my invention, what I claim as new, and desire to secure by Letters Patent, is—

In connection with a boiler, arranged at the top or side of hot-air flues in houses, the combination and arrangement of the perforated boiler-top with the perforated cover F, pivoted at f, the connecting-rod H, and the register B, when the parts referred to are constructed and arranged substantially in the manner and for the purposes set forth.
